CLAIM

The ornamental design for a rear intake port for an automobile, as shown and described.

DESCRIPTION

FIG. 1 is a front right top side isometric view of a driver side embodiment of the rear intake port for an automobile, showing my new design;

FIG. 2 is a rear left bottom isometric view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front right top isometric view of a passenger side embodiment of the rear intake port for an automobile showing my new design;

FIG. 10 is a rear left bottom isometric view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.
